DESIGN FOR A MUSICAL INSTRUMENT OF A FLUTE-LIKE NATURE

Elver J. Fitchhorn, Delaware, Ohio

Application May 2, 1939, Serial No. 84,726

Term of patent 14 years

To all whom it may concern:

Be it known that I, Elver J. Fitchhorn, a citizen of the United States, residing at Delaware, in the county of Delaware and State of Ohio, have invented a new, original, and ornamental Design for a Musical Instrument of a Flute-like Nature, of which the following is a specification, reference being had to the accompanying drawing, forming a part thereof.

Fig. 1 is a perspective view of a Musical Instrument of a Flute-like Nature showing my new design;

Fig. 2 is a top plan view thereof;

Fig. 3 is an end elevational view thereof.

I claim:

The ornamental design for a musical instrument of a flute-like nature, as shown.

ELVER J. FITCHHORN.
